UNITED STATES PATENT OFFICE.

EMIL TANKE, OF FALKENHAGEN, NEAR SERGEFELD KRS. OSTHAVELLAND, GERMANY,
ASSIGNOR, BY MESNE ASSIGNMENTS, TO AUTOMATIC ELECTRIC INC., OF CHICAGO,
ILLINOIS, A CORPORATION OF DELAWARE.

TELEPHONE SYSTEM.

Application filed September 1, 1921, Serial No. 497,572, and in Germany September 25, 1913.

The present invention is a modification of the circuit arrangements for telephone installations described in the German Patent Number 275,655. In that patent the subscribers' lines are grouped according to the frequency of their calls, and provision is made at the first number impulse receiver for determining whether the calling line shall be connected or not to an operator's position, that is whether the call is to be set up on the semi-automatic or full automatic systems. According to the above patent, these circuit changes are made dependent on certain switching devices at the calling stations or at the exchange, which are differently arranged according to the system to which the subscribers belong. These switching devices directly actuate the members which connect up the operating positions. In installations in which repeaters are inserted between the calling lines and the first number impulse receivers, this direct action could only be effected over special leads provided for the purpose. In the modification according to the present invention, these special leads are not required and the devices for connecting up an operator's position are controlled not directly by the characteristic differences imposed on the calling subscriber's line, or on a group of such lines, but indirectly from the repeater. This arrangement enables the repeaters, as well as the first number impulse receivers, to be used in common for setting up a call either on the full automatic or semi-automatic systems.

According as certain circuit changes are, or are not, effected at the repeater, the devices for connecting up an operator's position will, or will not, be actuated. The repeaters may be at the same exchange as the first number receivers, or at a different exchange. Also the preselecting devices may be at the same exchange as the repeaters, or they may be placed in different exchanges. The circuit changes at the repeater can be effected by means of a relay at the repeater itself. The distinguishing characteristics which control the action of the relay, may be imposed either at the subscriber's station or at the exchange. In the latter case, this characteristic may be supplied by special contact arms or battery or other potentials imposed at the preselecting devices. If the

connection is set up over more than one pre-selecting device, and the subscribers' lines are grouped at the exchange according as they belong to the full or semi-automatic systems, the distinguishing characteristics are preferably imposed at the selectors of the last preselecting step. They may, however, be imposed at the selectors of the first pre-selecting step, if the succeeding preselecting devices are to be used in common for setting up a call on either system. The relay at the repeater is then operated over the selectors of the second or other succeeding pre-selecting device.

Besides the circuit changes, which connect up, or prevent the connection of, an operator's position, other changes are effected according to the invention, which render the operation more efficient. For instance, circuits which are necessary for the full automatic, but are not required for the semi-automatic working, are cut off because they may cause unnecessary noises in the receiver of the operator.

Figs. 1 and 2 of the accompanying drawing show by way of example circuit connections according to the invention, applied to an installation with two preselecting devices, VW_1 and VW_2 .

If the frequently calling subscriber V , whose station is equipped for full automatic working, calls up, the two preselectors VW_1 and VW_2 are set in known manner.

By the setting of the second preselector VW_2 , relays A and B at the repeater U, are energized. Relay A by closing its front contact 100, closes the circuit of relay V_1 from earth, battery V_1 , 100, 101, earth. Relay C is also energized when the arms of the preselector VW_2 reach the repeater, but it is slow acting, so that contact 129 in the circuit of a relay S is already opened, when the contact 103 of relay C is closed, so that relay S is not energized. The lead c of the group selector GW_1 (Fig. 2) is earthed at contact 104 of relay V_1 , so that relay C' is energized from earth, battery, off normal contact k_1 , C_1 , lead c , 104, earth. Relay C' at 105 connects a relay C_2 at GW_1 to the c lead, so that C_2 is also energized and locks itself over a contact 106 in a circuit independent of C' from earth, battery C_2 , 106, off normal contact 107, c , 104, earth. At

contact 108, winding II of relay B_1 is connected to the c lead by relay C_1 and relay B_1 is energized.

Winding III of relay B_1 is connected to the b lead over 109 and 111, and relay A_1 to the a lead at 110. Winding III of relay B_1 is connected over the front contact 111 of relay B_1 , so that this winding can only be energized over the b lead after its winding II has been connected to the c lead. Although contact 112 has been closed by relay B_1 and contact 113 by relay C' , relay DC cannot be energized over the g lead, since the necessary potential has not been applied to the d arm of the preselector VW_{II} .

The further setting up of the call is immaterial for the invention; the action is briefly, as follows:—The first series of impulses sent out by the subscriber V is transmitted by relay A at the repeater U , and relay A_1 at the group selector GW_1 , and energizes the lifting magnet H over contacts 115 of relay A_1 and 116 of relay B_1 . When relay V_2 at the repeater is energized at the first impulse from earth, battery, V_2 , 117, 100', 101, earth it causes battery to be applied at 118 to the b lead and thereby a circuit to be closed for relay B_1 over its winding III from earth battery, resistance w , 119, 118, 144, b , 139, III, 109, winding III of B_1 , earth. The excitation of relay B_1 is thus independent of relay C_1 , which at the first lifting step of the group selector GW_1 is de-energized in consequence of the opening of k_1 , but in consequence of its slow action, keeps its armature attracted for a time sufficient to allow the winding III of B_1 to be energized before winding II is cut off at 108. Relay B_1 remains energized during the series of impulses, while relay B at the repeater is short circuited and thereby de-energized in consequence of the closing of contact 120 of relay V_2 .

After the last lifting impulse, relay A at the repeater is continuously energized and in consequence of the opening of contact 100', relay V_2 is de-energized. The short circuit of relay B is removed at 120, and this relay is energized over the subscriber's loop in series with relay A . At contact 114 earth is now permanently cut off from the lead a and relay A_1 at GW_1 is de-energized. Relay V_2 , when de-energized, disconnects battery at 118 from the b lead, so that the circuit of winding III of relay B_1 is opened and the relay is de-energized, since relay C' is de-energized and contact 108 is already open. Relay C_2 remains energized, since the c lead is earthed by relay V_1 at 104, or by relay V_2 at 121.

When both relays A_1 and B_1 release their armatures the circuit of the rotary magnet D is closed at 122 and 123 from earth, battery, interrupter U , off normal contact k , closed at the first lifting step, D , contact 124

of relay C_2 , 123, 122, earth. As soon as an idle line is found, relay B_1 which is connected to the outgoing lead c' over contact 109 is energized. Contact 123 is opened and magnet D de-energized. At the first rotary step, contact 107 is opened and contact 107' closed, so that relay C_2 is maintained energized over contact 125 which is dependent on B_1 . When relay B_1 is energized, 125 is opened; relay C_2 releases its armature and closes thereby the contact 109'. The engaged potential, earth, is then applied at 126 to the outgoing c' lead over relay MR , while relay B_1 connects itself over contact 125 and contact 107' to the incoming lead c . Relay MR is energized at the same time with relay B_1 over lead c' . During the call, relays A and B as well as V_1 at the repeater, and relay B_1 at the group selector GW_1 are energized.

If the subscriber V is the first to restore his receiver at the end of the conversation, relays A , B and V_1 at the repeater are de-energized. At 104, earth is cut off from the lead c , so that relay B_1 at the first group selector is de-energized. Relay B_1 at 126 opens the circuit of relay MR . Contact 127 is closed and the release circuit for the group selector GW_1 is closed from earth, 127, 128, M , k_2 , battery, earth. Since relay C is still energized relay S at the repeater U is energized when contact 102 of relay V_1 is closed in a circuit from earth, battery, S , 102, 103, 129, earth. Relay S also at 130 short circuits relay C , which is thereby de-energized, and then opens at 103 the circuit of relay S ; the preselectors VW_1 and VW_{II} are thereby released in known manner, so that the normal condition of the circuit is again established.

If the wanted subscriber hangs up first, the relay MR of the group selector GW_1 is de-energized by the interruption of the current flowing over c' at the selectors which succeed the group selector GW_1 . The circuit of the release magnet M is closed over contacts 145 and 127'. The lead c is opened at 107' when the group selector returns to its normal position, so that windings I and II of relay B_1 are also de-energized. The release of the repeater U , and the preselectors VW_1 and VW_{II} is effected when the receiver is restored at the calling subscriber's station.

When the subscriber W calls, the preselectors VW_1 and VW_{II} are first set in known manner and when relay T at the preselector VW_{II} is energized, it closes contact 131 and battery is applied to the lead g . The further processes on the engagement of the repeater and the first group selector are at first the same as those above described. When relay C' is energized, however, not only are the relays B_1 and C_2 at the first group selector energized, but also a relay DC at the repeater in a circuit from earth, 113, 112, g lead, DC, 131, battery, earth. Re-

lay DC when energized, by opening the contact 132, prevents the *a* lead from being earthed, and by opening 119, prevents the battery from being applied to the *b* lead, so that when the operator is connected up to the line, any knocking in her receiver is avoided. At the same time, relay DC connects at 133 the motor magnet D_1 , of the service selector DW in a circuit from earth, 10 133, 134, D_1 , interrupter U_1 , battery, earth. The service selector seeks for an idle line to an operating position, and when this is found and relay T_1 is thereby energized, remains stationary; relay T_1 locks itself over 15 135 in a circuit independent of relay DC and connects at 136 and 137 the operator's instrument set to the calling line. The operator then enquires for the wanted number and sets the sender in known manner, where- 20 by relay T_2 is energized.

Relay T_2 at the contacts 138 and 139 cuts off the calling line from the leads *a* and *b* during the impulse transmission. Relay T_2 also over its contact 140 connects earth which 25 has been applied by relay V_1 at 104 to the *c* lead, to the lead *g*, so that when relay C' at the group selector GW_1 is de-energized by *k*, being opened at the first lifting step relay DC still remains energized. Relay T_2 , 30 also at 141 earths the lead *d*, so that relay T_1 is also independent of contact 142 of relay C' . The series of impulses transmitted by the service selector set, as above described, the group selector GW_1 . At the end of the 35 series of impulses the circuit of relay T_2 is interrupted at the operator's position or at the sender, so that the calling line is through connected to the wanted subscriber at 138 and 139. At 140 the circuit of relay DC is 40 opened and at 141 or 143 also the circuit of relay T_1 ; when relay T_1 is de-energized the operator is cut off from the connection. The release of the connection is effected when the wanted subscriber restores his receiver 45 as above described. If the subscriber W is the first to hang up his receiver, relays A, B and V_1 are deenergized as before at the repeater U_1 . Relay S is energized and effects the changes described above.

50 What I claim and desire to protect by Letters Patent is:—

1. In a telephone system, lines of two different kinds, a trunk line terminating in an automatic switch, a repeater included in said 55 trunk line, means for extending calling lines of both kinds to said repeater, a trunk line leading to an operator's position, and discriminating means in said repeater effective only if the calling line is of a particular kind 60 for connecting said switch with said second trunk line.

2. In a telephone system, lines of two different kinds, a trunk line terminating in an automatic switch, means for extending calling 65 lines of both kinds to said switch, a

trunk line leading to an operator's position, discriminating means effective only if the calling line is of a particular kind for connecting said switch with said second trunk line, and means for temporarily opening 70 said first trunk line while the operator is controlling said switch.

3. In a telephone system, lines of two different kinds, a trunk line terminating in an automatic switch, a repeater included in said 75 trunk line, means for extending calling lines of both kinds to said repeater, a trunk line leading to an operator's position, and discriminating means in said repeater effective only if the calling line is of a particular kind 80 for connecting said trunk lines to establish a three way connection involving the calling line, said switch, and the operator's position.

4. In a telephone system, lines of two different kinds, a trunk line terminating in an 85 automatic switch, means for extending calling lines of both kinds to said switch, a trunk line leading to an operator's position, discriminating means effective only if the calling line is of a particular kind for connecting 90 said trunk lines to establish a three way connection involving the calling line, said switch, and the operator's position, and means for cutting the calling line out of the connection while the operator is controlling 95 said switch.

5. In a telephone system, lines of two different kinds, a trunk line comprising two normally connected sections, the second section terminating in an automatic switch, a 100 normally disconnected branch of said second section extending to an operator's position, means for connecting any calling line with the first section of said trunk line, and discriminating means effective only if the calling line is of a particular kind for connecting up said branch. 105

6. In a telephone system, lines of two different kinds, a trunk line comprising two normally connected sections, the second section terminating in an automatic switch, a 110 normally disconnected branch of said second section extending to an operator's position, means for connecting any calling line with the first section of said trunk line, discriminating means effective only if the calling line is of a particular kind for connecting up said branch, and means for separating said sections while the operator controls said switch. 115

7. In a telephone system, lines of two different kinds, a trunk line comprising two normally connected sections, the second section terminating in an automatic switch, a normally disconnected branch of said second section 120 extending to an operator's position, means for connecting any calling line with the first section of said trunk line, discriminating means effective only if the calling line is of a particular kind for connecting up said 125

branch, means for separating said sections while the operator controls said switch, and means whereby the two sections are again connected and the branch is disconnected 5 after the operation of said switch is completed.

8. In a telephone system, manual and automatic subscribers' lines, automatic switches at the exchange for connecting said lines, 10 preselectors inserted in the system between the manual lines and said switches, other preselectors inserted between the automatic lines and said switches, said preselectors con-

stituting means for connecting any calling line to an idle switch, a switching device for 15 further extending to an operator's switch-board a calling line which has been connected to a switch, a conductor multiplied in the banks of both manual and automatic line preselectors, means included only in the 20 manual preselectors for placing a potential on said conductor, and a relay controlled over said conductor for controlling said switching device.

EMIL TANKE.
